EXHAUST PIPE EXTENSION OR SIMILAR
ARTICLE FOR AN AUTOMOBILE

George C. Knight, Detroit, Mich., assignor to George C. Knight Company, Detroit, Mich., a corporation of Michigan

Application April 7, 1950, Serial No. 9,048

Term of patent 14 years

(Cl. D14—6)

To all whom it may concern:

Be it known that I, George C. Knight, a citizen of the United States, residing at 14129 Rutland, Detroit 27, Michigan, have invented a new, original, and ornamental Design for an Exhaust Pipe Extension or Similar Article for an Automobile, of which the following is a specification, reference being had to the accompanying drawings, forming a part thereof.

Fig. 1 is a plan view of an exhaust pipe extension or similar article for an automobile embodying my invention.

Fig. 2 is a side elevational view thereof.

Fig. 3 is a rear view thereof.

Fig. 4 is a perspective view as seen from the side opposite from that shown in Fig. 2.

Figs. 5 and 6 are sectional views taken substantially on the lines 5—5 and 6—6 of Fig. 1, looking in the direction of the arrows.

The characteristic features of my design reside in the portions shown by means of full lines in the drawing.

I claim:

The ornamental design for an exhaust pipe extension or similar article for an automobile, substantially as shown and described.

GEORGE C. KNIGHT.
